BEER CAN

Ronald Victor King, New York, N. Y.

Application December 17, 1953, Serial No. 28,118

Term of patent 14 years

(Cl. D58—17)

FIG. 1.

FIG. 3.

FIG. 2.

FIG. 4.

Fig. 1 is an elevational side view of a beer can, showing my new design.

Fig. 2 is a top plan view thereof.

Fig. 3 is a front view thereof, taken on a reduced scale.

Fig. 4 is a front elevational view thereof taken on a reduced scale, showing the ring-shaped handle portions in different positions of pivotal adjustment.

The side not shown is identical to the side shown.

I claim:

The ornamental design for a beer can, substantially as shown and described.
